UNITED STATES PATENT OFFICE

150,801

DESIGN FOR A PICTURE-CONTAINING BRACELET OR SIMILAR ARTICLE

Wolf E. Meierowitz, Providence, R. I.

Application January 16, 1947, Serial No. 136,183

Term of patent 3½ years

(Cl. D45—4)

To all whom it may concern:

Be it known that I, Wolf E. Meierowitz, a citizen of the United States, residing at Providence, in the county of Providence and State of Rhode Island, have invented a new, original, and ornamental Design for a Picture-Containing Bracelet or Similar Article, of which the following is a specification, reference being had to the accompanying drawing, constituting a part thereof.

Fig. 1 is a front plan view of a picture-containing bracelet or similar article, showing my new design;

Fig. 2 is a side elevation; and
Fig. 3 is a rear plan view.

I claim:

The ornamental design for a picture-containing bracelet or similar article, substantially as shown.

WOLF E. MEIEROWITZ.
